(57) **CLAIM**

We claim the ornamental design for a cosmetic bottle, as shown and described.

DESCRIPTION

FIG. 1 is a top perspective view of a cosmetic bottle showing our new design;

FIG. 2 is a front view of the bottle shown in FIG. 1;

FIG. 3 is a back view of the bottle shown in FIG. 1;

FIG. 4 is a right side view of the bottle shown in FIG. 1;

FIG. 5 is a left side view of the bottle shown in FIG. 1; FIG. 6 is a top view of the bottle shown in FIG. 1, the inside and opposing side details omitted for ease of understanding; and,

FIG. 7 is a bottom view of the bottle shown in FIG. 1, the inside and opposing side details omitted for ease of understanding.

The evenly-dashed broken lines in the drawings illustrate the portions of the cosmetic bottle that form no part of the claim.
